UNITED STATES PATENT OFFICE

2,567,625

FOOT TREATING DEVICE

Louis Ball Triplett, deceased, late of Pasadena, Calif., by Helen A. Triplett, executrix, Coronado, Calif., assignor to Helen A. Triplett, Santa Barbara, Calif.

Application June 24, 1949, Serial No. 101,102

1 Claim. (Cl. 128—25)

1

The present invention relates to an improved device for flexing, exercising and massaging the human foot, for the purpose of adjusting the joints and bones thereof into proper and normal relative positions, relaxing the muscles and consequently resting the foot, reestablishing circulation of blood so as to overcome the effects of stairs. The present invention is in the nature of an improvement of the device shown in prior Patent 2,187,920, issued January 23, 1940, to the inventor of the present improvement.

The object of the present invention is to provide a structure which, while achieving the purposes and retaining the advantages of the structure shown in the above-mentioned patent, will provide a better distribution of the flexing action through the foot structure, provide a better control over the exercising procedure by the user and afford a wider range of foot manipulations.

These and other and further objects and advantages will be made apparent in the following specification and claim.

In the accompanying drawing,

Fig. 1 is a generally perspective view showing a foot exercising device embodying the improvements of the present invention;

Fig. 2 is a detail sectional view substantially on line 2—2 of Fig. 1.

Fig. 3 is a detail sectional view substantially on line 3—3 of Fig. 1; and

Fig. 4 is a side elevational view showing the manner of using the device.

Referring to the drawing, the device is illustrated as comprising a U-shaped base member 1 which includes a transverse floor engaging portion 2, and slide members 3, the forward ends of the latter being bent downwardly and provided with rubber or fibre floor engaging tips as at 4. By this arrangement the base member is inclined upwardly as is clearly shown in Fig. 4.

The side members 3 support the ends of a transverse platform member 5 the ends of which are bent around the members 3, as indicated at 6, to secure member 5 in place. A plate member 7 is riveted, or otherwise secured, to member 5 as at 8. A generally U-shaped frame 9, comprising a transverse portion 10 and upwardly extending arms 11, is pivotally secured to the rear edge of plate 7 by means of a tongue 12 extending from the rear edge of the plate and bent around portion 10 of the frame, as best shown in Figs. 2 and 4. The arms 11 include upwardly and forwardly inclined portions 13 and forwardly extending portions 14. An arcuate bridge member 15 has its ends 16 bent around the frame

2

portions 14 and the inner face of the bridge is provided with a foot engaging member 17 which is formed of felt, sponge rubber or other yielding material.

5 The arms 11 are normally held in a plane substantially at right angles to the plane of members 3 by means of springs 18, each encircling a portion 10 of the frame and having one end anchored in plate 7, as at 19, the other end being bent around one of the arms 11 as indicated at 20. Springs 18 tend to swing the frame 9 rearwardly, or clockwise as viewed in Figs. 1 and 4 and such movement is limited by the engagement of the arms 11 with a stop member 21 which is bent upwardly from the rear edge of transverse member 5.

A second U-shaped frame 22, which includes a transverse portion 23 and arms 24, is pivotally connected at the forward edge of plate 7 by a tongue 25 extending therefrom and bent over the portion 23 of the frame 22. The arms 24 extend through openings 26 in a transverse member 27 slidably mounted at its ends on portions 13 of frame 9.

25 Above member 27 a plate 28 is secured to the ends of arms 24 as by nuts 29. A block 30 is secured to plate 28, or by screws 31, and an elongated relatively narrow soft resilient foot engaging pad 32, preferably of sponge rubber, covered with a strip of leather 33, is cemented to block 31.

30 In the use of the device, it is normally rested upon the floor and the foot to be treated is placed as shown in Fig. 4, and the front part of the foot, such as the toes, or the toes and the metatarsal joints, are passed under the bridge 15. The arch of the foot is brought into engagement with the arch engaging pad 32 at a position where upward pressure is desired, the foot is then shifted forward, or in the direction of the arrows in Fig. 4, to swing the bridge 15 toward the position indicated by the dotted lines in the latter figure and to swing the arch engaging pad to the position also indicated by dotted lines. Owing to the fact that the pad 32

35 swings on an arc generated around the pivot means 23—25, and the bridge 15 moves along an arc, generated around the pivot means 10—12, the bridge 15 will move downward relative to the arch engaging pad 32, or conversely the arch engaging pad 32 may be considered as having an upward movement relative to the bridge 15. As a result the arch engaging pad 32 presses upward against the bottom of the foot and the bridge presses downwardly against the upper

40 45 50 55 forward part of the foot, thereby convexly flex-

ing the arch of the foot. In proceeding with this treatment, the foot may be shifted from one side to the other and may be moved forwardly and rearwardly relative to the foot engaging parts, so that the scope of the treatment may be distributed over a relatively large area, thereby accomplishing complete manipulation massaging effect and exercising of the foot structure.

By forming the arch engaging pad 32 in transversely elongated arcuate shape with the end portions sloping downwardly from the center, additional and advantageous manipulation of the foot is made possible as compared with the arrangement of Patent 2,187,920 above-mentioned. When the parts are rocked forward with the foot in normal upright position the flexing action is distributed more uniformly and effectively across the foot structure. Furthermore the foot can be turned on the pad 32 with one side portion of the foot finding support on the adjacent end portion of the pad as a pivot, as shown diagrammatically in dotted lines *a* and *b* in Fig. 5. Depending on whether the foot is held in one twisted position throughout the forward and downward motion of the apparatus, is twisted to one side simultaneously with the forward movement of the apparatus, or is rolled from one side to the other as the apparatus swings forward, a different novel manipulation of the foot is obtained. In all of the manipulations with this improved device the underside of the foot has a degree of support that asserts a controlled but varying degree of reaction against the arch member 15 which is not afforded by the prior device in which the reaction is concentrated along the medial line of the foot.

Furthermore in the present device the rearward inclination of the base member by the downward bending of the tipped portions 4 pro-

vides a more efficient initial position of the foot and a more effective arcuate movement without interfering with the relative positions of the members 15 and 32.

5 What is claimed is:

In a foot treating device which comprises, in combination, an elongated padded member for transversely engaging the bottom of the arch portion of the foot, and a generally arcuate bridge member positioned to engage the upper portion of a foot forwardly of the arch engaging padded member, said padded member and said bridge member being mounted for pivotal movement about eccentric centers, said padded member having a length at least equal to the width of the foot to be treated and to substantially the full width of the bridge member at its base, the forward and rear faces of the pad lying in substantially parallel planes, the foot contacting top face of the pad arching upwardly from each end to the center of the pad and forming a surface of single curvature at right angles to the planes of said forward and rear faces.
